CARBURETOR

Eugene H. Rustin, Brooklyn, N. Y.

Application April 3, 1933, Serial No. 664,245
Renewed April 21, 1934

5 Claims. (Cl. 261—72)

This invention relates to carburetors for internal combustion engines and has for the primary object, the provision of a device of the above-stated character whereby air and liquid fuel may be thoroughly mixed to produce an efficient and dry fuel which when ignited will provide maximum power and a minimum consumption of fuel.

Another object of this invention is the provision of a carburetor construction built in or 10 as a part of the fuel tank and is equipped with regulating valves for controlling both the air and liquid fuel to the mixing chamber of the carburetor and the flow of the mixed and vaporized fuel from the said chamber to the engine.

15 A further object of this invention is the provision of means for preventing flames due to the back-firing of the engine from igniting fuel in the carburetor or within the fuel tank.

20 A still further object of this invention is the provision of means for admitting heated air to the mixing chamber of the carburetor with a minimum amount of moisture therein and free of dirt and other foreign matter.

25 With these and other objects in view this invention consists in certain novel features of construction, combination and arrangement of parts to be hereinafter more fully described and claimed.

30 For a complete understanding of my invention, reference is to be had to the following description and accompanying drawings, in which

35 Figure 1 is a side elevation partly in section illustrating a carburetor constructed in accordance with my invention and showing the same installed to a fuel tank.

Figure 2 is a fragmentary vertical sectional view illustrating the same.

40 Figure 3 is a sectional view taken on the line 3—3 of Figure 2.

Figure 4 is a sectional view taken on the line 4—4 of Figure 2.

45 Figure 5 is a fragmentary view illustrating the combined closure and bearing for the rotatable control valve of the carburetor.

Figure 6 is a plan view illustrating the rotatable control valve.

Figure 7 is a sectional view taken on the line 7—7 of Figure 6.

Figure 8 is a sectional view taken on the line 50 8—8 of Figure 2.

Figure 9 is a perspective view illustrating one of the valves of the carburetor.

55 Referring in detail to the drawings, the numeral 1 indicates a fuel tank, the bottom wall of which is provided with an opening 2 surrounded by an

internally threaded flange 3 to which is threaded a combined valve mounting and closure cap 4. The opening 2 permits the assembling or placing in the tank 1 a carburetor mixing chamber 5 to which is connected by screw threads an outlet pipe 6 detachably connected to a coupling 7 which joins to the outlet pipe 6 a pipe 8. The coupling 7 is mounted in an opening formed in one of the walls of the tank 1 and is of such a construction to prevent leakage between the tank and the coupling and also permit separation of the pipes 6 and 8 when desired. The pipes 6 and 8, as shown in Figure 2, are of substantially L-shape and reversely arranged relative to each other with the pipe 8 detachably connected to a control valve 9 consisting of a casing 10 provided with inlet and outlet necks 11 and 12. The inlet neck 11 is preferably threaded to the pipe 8, while the outlet neck 12 is threaded to a pipe 13 suitably constructed for connection with the intake manifold 10 of an engine. Journaled in the valve casing 10 is a rotary valve 14 adapted for controlling the passage of fuel to the engine and is provided with a stem 15 journaled in an end wall of the casing and to which is connected a suitable operating medium 16. Between the stem 15 and the valve casing a suitable stuffing gland 17 is provided. The opposite end of the valve casing is fully open and internally screw threaded to permit the rotary valve to be placed in or removed from the valve casing. A closure 18 is threaded in the open end of the valve casing and forms a journal for one end of the rotary valve.

30 The mixing chamber 5 consists of an outer sleeve 19 having its upper end enlarged and internally threaded to receive the threaded end of the pipe 6. An inner sleeve 20 is formed integrally with the upper portion of the outer sleeve 19 and the lower ends of said sleeves terminate in alignment with the major portion of the inner sleeve 40 relatively spaced from the outer sleeve. The formation of the inner sleeve with the outer sleeve provides a valve seat 21 for a gravity seating valve 22, the latter provided with a bore to receive a stem 23 projecting slightly above the valve 22 and has threaded thereto a nut or similar element 24 for limiting the upward movement of the valve on the stem. However, the nut may be adjusted on the stem for the purpose of varying the movement of the valve relative to the stem. A spider 45 25 is located in the inner sleeve 20 and slidably supports the stem 23, the lower end of which is shaped to form a needle valve 26.

50 A closure 27 is removably secured to the lower end of the outer sleeve 19 and the inner sleeve 55

abuts said closure. The closure lies partially within the opening 2 of the tank and is spaced from the walls of said opening so that the fuel within the tank may gravitate freely into the 5 combined closure and valve mounting 4. The closure 27 is provided with double valve seats communicative with each other and with the interior of the inner sleeve and with the interior of the combined closure and valve mounting 4. 10 The double valve seats are superimposed and the uppermost valve seat is engaged by the needle valve 26 and the latter is urged in engagement therewith by a spring 28. The lower valve seat is engaged by a needle valve 29 adjustably mounted in the combined closure and valve mounting 4 so as to regulate the flow of fuel from the tank to the interior of the inner sleeve. The inner sleeve on the interior thereof forms a mixing 15 chamber and the spacing of the inner and outer sleeves provides an air chamber. The mixing and air chambers are in communication with each other by slots 30 formed in the lower portion of the inner sleeve and arranged preferably in substantial alinement with the upper valve seat of the closure 27 so that the air in the air chamber will be admitted to the mixing chamber in substantially the same plane with the admittance of fuel to the mixing chamber.

A removable cap 31 is carried by the combined 20 closure and valve mounting 4 to overlie the outer end of the needle valve and may be removed when it is desired to adjust the needle valve. A suitable packing 32 is provided for the needle valve and is adapted to retain the valve in any of its adjusted positions.

A neck 33 is in communication with the air chamber substantially intermediate the end of the outer sleeve and provides a combined coupling and stuffing gland between a wall of the fuel tank 40 and an air intake pipe 34. The pipe 34 is removably secured in the coupling and is of substantially L-shape with one leg portion thereof disposed vertically and preferably located adjacent a suitable heat source such as an exhaust manifold of an engine and mounted upon said leg is a moisture trap 35 adapted to admit air to the intake pipe with a minimum amount of moisture and foreign matter. The trap 35 is preferably of cylindrical shape having its upper end closed by an end wall and its lower end closed by a perforated wall on which is formed an attaching neck 36 to receive the intake pipe 34. A trap 35 of the character described admits air at its lower end and said air must travel upwardly before entering the intake pipe 34, thereby eliminating the possibility of excessive moisture passing with the said air into the intake pipe. Located within the neck 33 are spaced screens 37 through which the air must pass before entering the air chamber 50 within the outer sleeve 19 and thereby remove any foreign matter which may be moving with the air.

A portion of the pipe 13 is slightly enlarged to form a seat for a valve cage 38, the latter being 65 secured to said pipe 13 by a set bolt 39. The valve cage has a self-seating check valve 40 opened by the suction of the engine to which the pipe 13 is connected and in case of back pressure caused by back-firing of the engine will automatically shut 70 and prevent flames from igniting fuel within the pipes 8, 6 and the mixing chamber within the fuel tank, thereby reducing fire hazards to a minimum.

During non-operation of the carburetor or the 75 engine to which it is applied, the valves 40, 22 and

26 are in engagement with their respective seats and the valve 26 in engagement with its seat prevents entrance of fuel from the tank to the mixing chamber, obviating a possibility of the carburetor becoming flooded with fuel.

During the operation of the engine, the valves 40 and 22 are unseated by the suction of the engine and the unseating of the valve 22 opens the mixing chamber to the pipe 6 and also unseats the needle valve 26 from its seat, allowing the fuel from the fuel tank to enter the mixing chamber and the suction of the engine within said mixing chamber draws air therein which becomes thoroughly mixed with the fuel to vaporize and break up the latter into a substantially dry and highly combustible fuel capable of producing maximum power to the engine when ignited.

The pipe 8 has a comparatively small opening 41 adapted to admit air for mixing with the fuel prior to entering the engine.

From the foregoing description taken in connection with the accompanying drawings it will be seen that all of the various parts involved in this invention are readily accessible and that the parts located within the fuel tank may be conveniently assembled within the latter.

While I have shown and described the preferred embodiment of my invention, it will be understood that minor changes in construction, combination and arrangement of parts may be made without departing from the spirit and scope of my invention, as claimed.

Having described the invention, I claim:

1. In combination with a fuel tank, a mixing chamber mounted in the fuel tank and having communication with the latter, means for regulating the fuel from the fuel tank to the mixing chamber, means for admitting air to the mixing chamber, an outlet manifold connected to the mixing chamber and to an intake manifold of an engine, a suction operated valve between the outlet manifold and the mixing chamber, and means affected by the movement of the suction valve to positively control the fuel from the tank to the mixing chamber.

2. A carburetor comprising a fuel tank, relatively spaced and integrally connected inner and outer sleeves in said tank, an outlet manifold connected to said sleeves and to the intake manifold of an engine, a suction controlled valve between the outlet manifold and the inner sleeve, a valve actuated by the suction valve to open and close the inner sleeve to the tank, a regulator valve for controlling the fuel from the tank to the inner sleeve, and means for admitting air to the inner sleeve.

3. A carburetor comprising a fuel tank, relatively spaced and integrally connected inner and outer sleeves in said tank, an outlet manifold connected to said sleeves and to the intake manifold of an engine, a suction controlled valve between the outlet manifold and the inner sleeve, a valve actuated by the suction valve to open and close the inner sleeve to the tank, a regulator valve for controlling the fuel from the tank to the inner sleeve, said inner sleeve having slots, and an air supply means connected to the outer sleeve.

4. A carburetor comprising a fuel tank, relatively spaced and integrally connected inner and outer sleeves in the tank and having their lower ends open, said inner sleeve having its upper end open and formed to provide a valve seat, an outlet manifold connected to the sleeves adjacent the seat and to an intake manifold of an engine,

a suction operated valve engaging the seat, a closure closing the lower ends of said sleeves, and having a passage in communication with the tank and provided with superimposed valve seats, 5 a needle valve operated by the suction valve to engage the upper seat of the superimposed seats, a regulating valve for engaging the lower seat of the superimposed seats, tension means for seating the needle valve, and means for admitting air to the inner sleeve.

5. A carburetor comprising a fuel tank, relatively spaced and integrally connected inner and outer sleeves in the tank and having their lower ends open, said inner sleeve having its upper 10 end open and formed to provide a valve seat, an outlet manifold connected to the sleeves adjacent

the seat and to an intake manifold of an engine, a suction operated valve engaging the seat, a closure closing the lower ends of said sleeves and having a passage in communication with the tank and provided with superimposed valve seats, a needle valve operated by the suction valve to engage the upper seat of the superimposed seats, a regulating valve for engaging the lower seat of the superimposed seats, tension means for seating the needle valve, said inner sleeve having slots to 10 establish communication between the interior thereof with the interior of the outer sleeve, and means for admitting air to the interior of the outer sleeve.
